UNITED STATES PATENT OFFICE.

LEROY HILLER TOWNER, OF MUSKOGEE, OKLAHOMA.

ATTACHMENT FOR EARTHWORKING-MACHINES.

1,346,432.

Specification of Letters Patent.

Patented July 13, 1920.

Application filed August 29, 1919. Serial No. 320,612.

To all whom it may concern:

Be it known that I, LEROY H. TOWNER, a citizen of the United States, residing at Muskogee, in the county of Muskogee and State of Oklahoma, have invented new and useful Improvements in Attachments for Earthworking-Machines for Preventing Side Draft or Side Skidding, of which the following is a specification.

10 My invention relates to an attachment for an earth working machine, such as a road grader, road drag, or the like, for engagement with the earth or road bed, to prevent side draft or side skidding of the machine.

15 An important object of the invention is to provide an anti-skidding rotatable disk, suitably connected with the earth working machine, and operating within the earth for a suitable depth, for forming positive means 20 to prevent side draft or skidding of the machine.

A further object of the invention is to provide simple and strong means to vertically adjust the anti-skidding disk, so that 25 it may be elevated above the earth to clear the same, during the transportation of the machine.

A further object of the invention is to provide an attachment of the above mentioned 30 character, which may be secured to the ordinary earth working machine without materially altering the construction of such machine.

A further object of the invention is to 35 provide an attachment of the above mentioned character, which is simple in construction, strong, durable, cheap to manufacture and is located in a position, in use, whereby it in no way impairs the operation 40 of the elements of the earth working machine.

Other objects and advantages of the invention will be apparent during the course 45 of the following description.

In the accompanying drawings forming a part of this specification, and in which like numerals are employed to designate like parts throughout the same.

Figure 1 is a side elevation of the anti-skidding attachment embodying my invention.

Fig. 2 is a plan view of the same, and

Fig. 3 is a transverse section taken on line

3—3 of Fig. 1.

55 In the drawings, wherein for the purpose

of illustration is shown a preferred embodiment of my invention, the numeral 5 designates the frame of an earth working machine, such as a grader or drag, a combined grader and drag, or similar machine used for more or less similar purposes. The rear end of this machine is supported by an axle 6, having spindles 7, carrying wheels 8.

My attachment embodies a preferably V-shaped frame, designated as a whole by the numeral 9. This frame embodies side beams 10, preferably formed of angle irons, bent to provide rear parallel portions 11 and forward portions 12, which diverge forwardly, as shown. The beams 10 are rigidly connected, intermediate their ends, by a transverse plate 13, and a transverse angle iron 14, these parts being secured together by rivets 15 or the like.

At their forward ends the beams 10 engage hinge-straps 15', secured thereto by rivets 16 or the like, and these hinge-straps are disposed between pairs of hinge-straps 17 and pivoted thereto by bolts 18. The hinge-straps 17 are secured to the rear axle 6 by 70 rivets 19 or the like. It is thus seen that the frame 9 is pivoted to the rear portion of the frame 5, to swing in a substantially vertical plane.

Means are provided to raise and lower the frame 9, comprising an operating shaft or screw 20, having screw-threads 21. A hand wheel 22 is rigidly secured to the upper end of this operating shaft or raising screw. The shaft or screw 20 has its screw-threaded portion engaging within a support nut 23, provided with trunnions 24, pivoted within openings formed in brackets 25, in turn secured to the rear end 26 of the frame 5. The shaft or screw 20 is therefore pivotally supported and longitudinally adjustable by 90 rotating the same.

The lower end 26' of the shaft or screw 20 is loose and is rotatable within a sleeve 27 having no internal screw-threads formed upon a hollow coupling block 28, such end carrying a nut 29, rigidly secured thereto, and arranged within the hollow coupling block or element. It is thus seen that the shaft or screw 20 has a swiveled connection 105 with the coupling block or element 28.

Depending from this coupling block or element and preferably formed integral therewith is a flange 30, having an opening 31, pivotally receiving a U-bolt 32, which is 110

secured to the transverse angle iron 14 by nuts 33, said U-bolt passing through openings in the transverse angle iron.

The numeral 34 designates an anti-skid disk, the edge of which may be suitably sharpened. This disk has a central opening 35, receiving an axle 36. The anti-skid disk 34 is reinforced by castings 37, arranged upon opposite sides thereof, and having radial ribs 38, and hubs 39. The reinforcing castings 37 and disks 34 are secured together by rivets 40, while bolts 42 lock the hubs 39 to the axle 36.

The axle 36 is journaled in bearings 43, bolted or otherwise rigidly secured to the parallel portions 11 of the arms 10, as shown at 44. These bearings may be lubricated by grease cups 45, as shown.

The disk 34 has its upper portion covered by a curved guard 45', the forward end of which is attached to the transverse plate 13, as shown at 46. The rear end of this guard is secured to an inverted U-shaped support 47, which has its lower ends attached to the parallel portions 11.

In the operation, of the attachment, by proper rotation of the shaft or screw 20, the frame 9 may be lowered and the disk 34 will enter the earth or road bed for a suitable distance. It is obvious that this disk will then positively prevent side draft or skidding of the earth working machine. By turning the shaft 20 in an opposite direction, the frame 9 may be elevated so that the disk will be spaced from the soil for transportation purposes.

I wish it to be understood that the invention is in no sense restricted to the employment of a vertically swinging frame for connecting the disk with the earth working machine, as various other constructions may be employed which will permit of a vertical adjustment of the disk. It is to be also understood that the disk may be employed without the vertical adjustment, and the earth working machine operated with some degree of success.

It is to be understood that the form of my invention herewith shown and described is to be taken as a preferred example of the same, and that various changes in the shape,

size, and arrangement of parts may be resorted to without departing from the spirit of my invention, or the scope of the subjoined claims.

Having thus described my invention, I claim:

1. The combination with an earth working machine, of an earth engaging disk, a vertically swinging frame carrying the disk and pivoted to said machine, a raising screw, a support nut engaging the raising screw and pivoted upon said machine, means positively connecting the raising screw and swinging frame, and means to turn the screw.

2. The combination with an earth working machine, of an earth engaging disk, a vertically swinging frame carrying the disk and pivoted to said machine, a raising screw, a support nut engaging the raising screw and pivoted upon said machine, means to turn the raising screw, and a coupling member swiveled upon the lower end of the raising screw and pivotally and positively connected with the swinging frame.

3. An attachment for an earth working machine, comprising an approximately V-shaped frame, means for pivotally connecting the open end of the V-shaped frame with said machine, a rotatable disk arranged in the closed end of the V-shaped frame and connected therewith, a transverse member connected with said V-shaped frame, and raising and lowering means positively connected with the transverse member and adapted for positive connection with said machine.

4. An attachment for an earth working machine, comprising an approximately V-shaped frame, means for pivotally and positively connecting the open end of the V-shaped frame with said machine, a rotatable disk arranged within and connected with the closed end of the V-shaped frame, a transverse member connected with the V-shaped frame, and a raising screw positively connected with the transverse member and adapted for positive connection with said machine, all as and for the purposes set forth.

LEROY HILLER TOWNER.
